UNITED STATES PATENT OFFICE

GUSTAVE O. MATTER, OF PORTLAND, OREGON

ADVERTISING DISPLAY APPARATUS

Application filed April 2, 1929. Serial No. 351,850.

My invention relates primarily to apparatus for displaying words, names, phrases or illustrations in consecutive order of reading upon an endless moving member which 5 may be, therefore, comprehensively designated a legend-display exhibitor that constitutes an appliance applicable to any kind of automobile.

The mechanism for imparting motion to 10 the exhibitor is as an indispensable desideratum designed to be such as may be actuated at little or no expense for driving power and which is susceptible of considerable variation in respect to its form of embodiment.

15 My apparatus possesses a utility even when it is mounted upon a stationary support, but it has a distinct utility upon a traveling support, such for example as an automobile or the like, which is adapted in one way or another, without any extra expense for driving it, to impart motion with functioning effect to the exhibitor.

What constitutes my invention will be hereinafter described in detail and succinctly 25 defined in the appended claims.

Referring to the accompanying drawings,

Figure I is a longitudinal sectional view of one form of my apparatus in what I now regard as the preferred form of embodiment 30 of my invention.

Figure II is a bottom plan view of the subject matter of Figure I with the cover plate thereof removed.

Figure III is a longitudinal section on the line III—III of Figure I.

Figure IV is a cross section, partially in elevation, taken on the vertical line IV—IV of Figure I.

Figure V is a cross section on the vertical line V—V of Figure I.

Figure VI is a top plan view of the form of aerodynamic motor shown in Figure I, detached.

Figure VII is a diagrammatic side elevation of a portion of a car body having my apparatus affixed to the top thereof and in operative propinquity to the discharge end of an engine exhaust that is extended above the car body.

Figure VIII is a view similar to Figure

VII, but showing a modification of my apparatus in which, by extension of its driving shaft to a point below the car body, the aerodynamic motor is brought into operative propinquity to the exhaust pipe of the engine in 55 its ordinary disposition below the car body.

Figure IX is a perspective view of a roller detached, the roller serving to exemplify, it may be in itself, one complete form of exhibitor, but being also adapted to be employed as an actuating member for a flexible exhibitor.

Figure X is a perspective view showing a pair of rollers similar to the one shown in Figure IX in operative combination with a 65 flexible exhibitor having, instead of a horizontal movement, an up and down movement over said rollers.

Figure XI is a diagrammatic top plan view illustrating a modification of my invention in a form of embodiment which comprehends the employment of four rollers for carrying the exhibitor instead of the two shown in Figure I.

Figure XII illustrates, after the manner 75 employed in Figure XI, the use of three rollers instead of four.

Referring to the numerals on the drawings, 1 indicates a driving roller, and 2 a driven roller, that are journaled, respectively, in 80 bearing frames 3 and 4. Each of said frames is preferably provided with a top plate that is conveniently separable from the frame of which it forms a part. The top plate for the bearing frame 3 is indicated by the numeral 5, and that for the frame 4 is indicated by the numeral 6. They may be substantially duplicates, one of the other, except that the plate 6 is as shown in Figure I provided, for adjustment to and from the roller 85 1 of the roller 2, with a longitudinally disposed slot 8 corresponding to a similar corrective slot 9 in the bottom of the bearing frame 4.

The driven roller 2 consists of a cylinder 95 that is revolvably mounted on a shaft 11, whose opposite ends extend through the slots 8 and 9, respectively.

The shaft 11 is adjustably securable to the frame 4 as by nuts 12 and 13 threaded, re- 100

spectively, to the ends of the shaft and jamming, respectively, against washers 15, that are intermediate the frame and its top plate 6 when fixed thereto.

5 When the rollers 1 and 2 are vertically disposed, they should be provided at their respective bottoms with belt supporting means, such for example as a horizontal flange 16 on the roller 2. The driving roller 1 has, instead of the flange 16, a horizontally disposed gear 17 which incidentally serves the purpose of the flange 16.

The gear 17 intermeshes with a pinion 18 provided on a driving shaft 19 that is carried 15 in suitable bearings 20 and 21 provided in the cover 5 and in the bearing frame 3. The shaft 19 derives rotary motion from any suitable source of power, preferably as an aeromotor 23 that is revolvably fixed to one end 20 of the shaft 19 as by a nut 24, and which is provided with vanes 25 which are preferably cup-shaped.

The roller 1 being revolvably mounted upon a shaft 26 which is revolvably secured to the 25 frame 3 and cover 5 as by nuts 27 threaded to its opposite ends, cooperates with the roller 2 to carry and to impart motion to an endless belt 28 which constitutes one form of embodiment of my legend-display exhibitor.

30 The exhibitor 28 is kept sufficiently taut upon the rollers 1 and 2 by side members provided between and connecting the bearing frames 3 and 4 in which said rollers are revolvably mounted as above specified. Such 35 members may consist of transparent plates 30 and 31 which are assembled substantially as shown in Figure III, and which are preferably made of glass. A cover plate 32 and a bottom plate 33 which may be made of thin 40 sheet metal secured by any suitable means at their opposite ends, respectively, to the frames 3 and 4, and the cover plates 5 and 6 may be employed to supplement the plates 30 and 31 in the holding of the frames 3 and 45 4 in effectually rigid assemblage.

The aerodynamic motor may be driven by any suitable application of pneumatic energy. For example, it may be, without expense, rotated by the current of air that is 50 always generated simply by the usual travel of an automobile. It may be driven quite as effectively and as inexpensively, which is a desideratum, by the discharge of the exhaust pipe from the engine, not illustrated, of an automobile whether the automobile is in motion or not. Such an exhaust pipe 35 is indicated in Figure VII as extended above the top of a car body 36.

60 In Figure VIII the shaft 19 of the motor 23 is extended below its pinion 18, as indicated at 37, so as to bring the aeromotor in operative propinquity to an ordinary engine exhaust pipe 38 disposed below the car body 65 36.

The legend-display exhibitor 28, as above described, is an endless belt carried upon the rollers 1 and 2 and supported thereon by the flange 16 and gear 17, respectively. It may, however, consist simply of a revoluble member 40 if it is of sufficiently amplified diameter or transverse extent to adapt it to perform the display function of an exhibitor. Such a member in form of a cylindrical roller is illustrated sufficiently to convey the idea in Figure IX, but on a scale greatly reduced from the diameter thereof which would be employed if it were used to constitute of itself an exhibitor.

In Figure X two horizontally disposed rollers 41 and 42 are substituted for the vertical rollers 1 and 2 already described, and serve to afford support to and means of actuation for a vertically movable endless belt 43 as a substitute for the horizontally movable exhibitor 28.

It should be understood that when employed, the rollers 41 and 42 are correlative driven and driving rollers, and that they may be, by obvious changes of mechanism, actuated substantially in like manner as the rollers 1 and 2 are actuated.

In Figure XI four rollers 45, 46, 47, and 48, are shown as substituted, with similar driving effect upon an endless belt exhibitor 49, in place of the two roller form of embodiment of my invention shown in Figure I. The advantage of the exhibitor 49 in place of exhibitor 28 consists in the provision it makes of display end extensions 50 and 51 100 upon the exhibitor whereby advertising matter displayed upon the exhibitor may be viewed and read by advantageously stationed onlookers from one or more of the four sides of a car.

105 Another form of exhibitor is indicated by the numeral 53 in Figure XII, and consists of an endless belt supporting three rollers 54, 55, and 56. It is obvious from consideration and comparison of Figures III, IX, X, XI, and XII, that the number and relative disposition of the rollers employed may be, within practicable limits, varied at will, but it is deemed probable that there would be no advantage in any instance in employing more than four rollers, as shown in Figure XI.

110 The operation of my device may be briefly described as follows.

The outside surface of the exhibitor used in my apparatus, such, for example, as exhibitor 28, is provided with any preferred legend-display of advertising matter, such, for example, as was suggested at the outset in the foregoing general statement. This matter may be displayed in horizontal or vertical order of succession, as has been suggested, with the effect that whenever functioning motion is imparted to the exhibitor the display upon the exhibitor will attract attention and communicate to an onlooker 120 125 130

such information as the display matter on the exhibitor affords.

The exhibitor, of whatever form, is designed to be made of translucent material and to be illuminated at night as by electric lamps disposed within the space enclosed thereby. It may be as aforesaid made to operate not only when a car is travelling but also when the car is standing still as when the engine is idling.

10 If the apparatus be mounted upon a stationary support instead of upon a car, any suitable driving means instead of the motor 23, may be employed, but at some operating 15 expense, for actuating the exhibitor at will, either continuously or intermittently as may be desired.

What I claim is:

1. Advertising display apparatus, consisting of an appliance applicable to any automobile and embodying the combination of a movable endless legend-display exhibitor, with driving means consisting of an aero-motor having vanes adapted to be operated 25 by impact of pneumatic energy derived wholly from means employed for driving the vehicle.

2. Advertising display apparatus consisting of an appliance applicable to any automobile and embodying the combination of a movable display exhibitor operatively mounted on the outside of a vehicle, with an engine for driving the vehicle, and exhibitor driving mechanism operable by impact of 30 the engine exhaust.

35 In testimony whereof, I have hereunto set my hand.

GUSTAVE O. MATTER.
